Attorney.

UNITED STATES PATENT OFFICE.

FRANK E. WILLIAMS, OF ST. LOUIS, MISSOURI, ASSIGNOR TO POLAR ELECTRIC REFRIGERATOR CORPORATION, OF ST. LOUIS, MISSOURI, A CORPORATION OF MISSOURI.

REFRIGERATING APPARATUS.

Application filed August 6, 1925. Serial No. 48,511.

This invention relates to refrigerating apparatus, and more particularly to a cooler especially applicable to household refrigeration purposes. Two other applications for modified forms of refrigerating apparatus and one for a refrigerated cabinet including such an apparatus have been filed by the same inventor concurrently with this application.

10 An object of this invention is to provide a brine cooler having compartments or cavities therein adapted for receiving and cooling containers for making ice cubes and the like.

15 Another object is to provide an evaporator or vaporizer which may be rapidly and economically constructed and assembled.

Another object is to provide a vaporizer having cooling tubes and which is so constructed that bends in the tubes are unnecessary, thus avoiding the constrictions which usually occur at such bends in tubes and which impede the flow of refrigerant therethrough.

20 25 Another object is to provide a vaporizer in the interior of the brine tank whose configuration is such that the entire wall or sleeve of the tank surrounding each cooling compartment has juxtaposed to all portions thereof in the brine chamber respective portions of the vaporizer. This distribution of the several portions of the vaporizer in the tank contributes to an even cooling of all sides of the cooling compartment, supplementing the function of the circulating brine in this respect.

Another object is to provide means which will compensate automatically for the change in volume of the brine in the tank resulting from change in temperature so as to keep the brine chamber completely filled with brine at all times.

Other objects and advantages will appear in the course of the following description of a preferred embodiment of this invention.

In the accompanying drawings forming part of this specification, in which like numbers of reference denote like parts wherever they occur:

50 Figure 1 is a front elevation of the cooler of this invention;

Figure 2 is a sectional view taken on the line 2-2 in Figure 1;

Figure 3 is a sectional view taken on the line 3-3 in Figure 1; and

Figure 4 is a sectional view taken on the line 4-4 in Figure 2.

The illustrated structure consists of a sheet-metal brine tank 1 having a front wall 2, rear wall 3, side walls 4, top wall 5, and bottom wall 6. A shell 7 is secured to the top wall 5 and co-operates therewith to form an auxiliary chamber 8 disposed over the brine chamber proper and connected therewith by perforations 9 in the portion of the top wall 5 which serves as a partition between the said chambers. A horizontal row of vertically elongated apertures 10 are disposed in the lower portions of the front wall 2 and rear wall 3. Horizontal sleeves 70 or walls 11 connect the front and rear walls, the open ends of the said sleeves being in registration with the corresponding apertures 10, and the sleeve flanges 12 at the said ends making a fluid-tight joint with the 75 said front and rear walls. The ducts or cavities 13 enclosed by the sleeves 11 form compartments in which may be placed containers 14 adapted for freezing water into cubes of ice. The sleeves 11 also provide an 80 air cooling surface for the brine tank in addition to that afforded by the walls of the tank.

The front wall 2 has an aperture 15 in its upper portion to receive the cylindrical end 85 or boss 16 of a vaporizer header 17 disposed within the tank 1. The boss 16 has an opening 18 therethrough to afford access to the interior of the header 17, and the said opening is normally closed by means of 90 a cover 19, preferably secured thereto by means of screws 20. Screw-threaded openings 21 and 22 are provided in the cap 19 to facilitate making piping connections to a refrigerant circulating system, which connections are not shown since they are old and well known to those skilled in the art. The inner side of the opening 22 may also be connected to suitable means for controlling the level of liquid refrigerant in the header 17, such as a float-controlled valve, which means are also well known, and therefore not shown herein.

The boss 16 projects from a flange 23 on the front end of the header 17, and the said 100 flange 23 is connected in a fluid-tight manner 105

ner to the front wall 2, preferably by means of screws 24. The upper portion 25 of header 17 is preferably cylindrical in form, developing at its lower portion into a wide 5 and shallow hollow substantially rectangular distributing portion 26 extended horizontally in opposite directions from the centrally disposed upper portion 25. The distributing portion 26 comprises upper walls 27, 10 formed as continuations of the cylindrical wall 28, and a lower wall 29.

A plurality of bosses 34 with openings 35 therethrough are formed exteriorly on the lower wall 29 of header 17. Vertical tubes 15 38, closed at their lower ends by caps 30 screw threaded thereon, have their open upper ends inserted in the openings 35. In the present instance, there are four horizontal rows of such vertical tubes 38, each 20 row comprising six tubes. Of course, any suitable number of rows and tubes may be used, depending on the number of compartments 13 and the size of the cooler. The two intermediate rows pass between respective 25 adjacent sleeves 11, and each of the outer rows is interposed between a corresponding side wall 4 and an adjacent sleeve 11. The pipes 38 are secured in the openings 35 in a fluid-tight manner, being preferably soldered thereto. A block 31 of wood or wood-like material rests on the tank bottom 6, and supports an angle-iron frame 32 disposed around the margin of the tank. The caps 30 of those tubes 38 disposed about the margin 25 of the header portion 26 bear on the frame 32.

Liquid refrigerant, preferably sulphur dioxide, is supplied to the upper chamber 39 in header 17 through opening 22 therein 40 from any suitable compressing and liquefying apparatus included in the refrigerant circulating system. The liquid refrigerant flows into chamber 39 and shallow chamber 40 of hollow header 17, and thence down the tubes 38 to the bottom thereof. The liquid boils in the evaporator comprising the said header and pipes, absorbing heat from the surrounding brine in the sheet metal tank 1. The vapor arising in the pipes and header 45 eventually reaches the vapor space in the upper portion of the chamber 39, from whence it is drawn off by the suction of the compressor included in the refrigerant circulating system. The term brine as used herein is to be construed broadly as including any suitable anti-freezing solution, such as alcohol, sodium chloride, calcium chloride, and the like, the latter solution being preferable. It is worthy of note that with this 50 construction the cooling compartments or cavities 13 are surrounded on all sides by portions of the evaporator, thus insuring a comparatively evenly distributed cooling effect on all sides of the compartments 13.

55 The evenness of cooling is, of course, further

improved by the circulation of the brine in the tank 1.

It is preferable to keep the tank entirely filled with brine at all times, so that the upper portion of the tank cools as effectively as the lower portion. To this end the auxiliary chamber 8 is provided on top of the tank. The top wall of the chamber 8 enlarges or bends upwardly at 33 to form an air pocket 37, which opens laterally into a nipple 41 secured thereto, and having a cap 42 screw threaded thereon and provided with an opening 43 therein. The tank and auxiliary chamber are filled with brine through the nipple 41, the cap 42, of course, 75 having been removed for the purpose. Cap 42, when screwed on the nipple 41, prevents a too rapid evaporation of the brine from the tank, but permits enough air to pass through the opening 43 therein to equalize the pressure on the inside and outside of the tank when the volume of the brine changes with the temperature. When the volume of the brine contracts, brine flows from the auxiliary chamber 8 through the perforations 9 80 into the brine chamber proper, and when the brine therein expands, the excess passes up through the openings 9 into the chamber 8. A valve 44 may be connected to the lower portion of the tank to drain the brine therefrom as desired. An opening 45 may be made in the frame 32 adjacent the valve 44 to facilitate the flow of brine from the inside of the frame to the valve. Nipple 41 and valve 44 are connected to a suitable hose 85 or flexible tubing connected to suitable vessels when respectively filling and emptying the tank 1.

Having thus fully described this invention, I hereby reserve the benefit of all changes in form, arrangement, order, or use of parts, as it is evident that many minor changes may be made therein without departing from the spirit of this invention or the scope of the following claims.

I claim:

1. A hollow header for a refrigerant vaporizer having a main chamber and a relatively thinner distributing chamber opening from the main chamber, the thinner chamber having an extended lateral wall provided with a plurality of pipe-connecting openings therethrough.

2. A hollow header for a refrigerant vaporizer having a relatively thin and wide horizontally-extended distributing chamber enlarging upwardly at its middle portion to form a vapor-receiving chamber.

3. A brine tank having a shell secured to the top wall and co-operating therewith to form a second chamber superposed on the main chamber in the tank, the portion of the top wall partitioning the said chambers being perforated.

4. A brine tank having a shell secured to

the top wall and co-operating therewith to form a second chamber superposed on and communicating with the main chamber in the tank, and means disposed in the upper portion of the second chamber to maintain the top surface of the brine therein at atmospheric pressure.

5. A brine tank having a shell secured to the top wall and co-operating therewith to form a second chamber superposed on and communicating with the main chamber in the tank, a portion of the shell bulging upwardly above its upper side, a nipple connected laterally to the upwardly bulging portion, and a perforated cap on the outer end of the nipple.

10. A refrigerating apparatus comprising a tank having a series of ducts extending from the front and rear faces thereof, a header disposed in the upper portion of said tank, said header embodying a main chamber and a lower distributing chamber opening from the main chamber and extending laterally from the opposite sides thereof and 25 a plurality of tubes depending from the bottom of said distributing chamber and having their lower ends closed.

15. A refrigerating apparatus comprising a tank having a plurality of horizontally disposed ducts opening from the front to the rear faces of said tank, there being an auxiliary chamber arranged on the top of said tank and communicating therewith, a vaporizer header embodying main and distributing chambers, said distributing chamber presenting a wide and shallow hollow

space substantially rectangular in form, and a plurality of vertical tubes closed at their lower ends and having their upper ends connected to the base portion of said distributing chamber.

20. A refrigerating apparatus comprising a tank having a plurality of apertures extending horizontally thereof, a shelf portion arranged on the top of said tank and defining an auxiliary chamber in communication with said tank, a vaporizer header disposed within the upper portion of said tank, the upper portion of said header being cylindrical in form, developing at its lower portion into a wide and shallow hollow substantially rectangular distributing portion 45 extending horizontally in opposite directions, and vertical tubes closed at lower ends having their upper ends connected to the 50 base portion of said header.

25. A refrigerating apparatus comprising a tank having a plurality of apertures extending horizontally thereof, a vaporizer header disposed within the upper portion 55 of said tank, the upper portion of said header being cylindrical in form, developing at its lower portion into a wide and shallow hollow distributing portion extending horizontally in opposite directions and 60 vertical tubes closed at their lower ends and having their upper ends connected to the base portion of said header.

30. In testimony whereof I hereunto affix my signature.

FRANK E. WILLIAMS.
